MAGNETOSTRICTIVE LIGHT VALVE

William J. Herdman, South Orange, N. J., assignor to Wired Radio, Inc., New York, N. Y., a corporation of Delaware

Application November 1, 1930, Serial No. 492,738

3 Claims. (Cl. 88—61)

My invention pertains in general to light valves and specifically relates to a light valve operated by magnetostriction.

It has been found that ferromagnetic substances, particularly nickel and nickel-steel alloys, evidence a mechanical deformation under the influence of a magnetic field. This phenomenon is sometimes referred to as the Joule effect, being named for Joule, who made early investigations in magnetostriction. Certain ferromagnetic metals possess more marked magnetostrictive properties than others. I have found that a steel alloy containing 46 percent of nickel exhibits a marked mechanical expansion when magnetized; on the other hand, pure nickel exhibits mechanical contraction when magnetized. In United States Patent No. 1,467,318, issued to me September 11, 1923, and entitled Electron discharge device, I have disclosed the use of such magnetostrictive elements in a novel type of electron discharge device. My present invention is directed to controlling, by means of magnetostriction, a light beam incident upon a photosensitive device.

One of the objects of my invention consists in providing a light valve employing magnetostrictive means to control a light beam in accordance with an alternating or other variable current.

Another object of my invention consists in providing an arrangement of light valve in which a magnetostrictive element is interposed between a source of light and photosensitive means.

A further object comprises producing means for controlling the intensity of a light beam incident upon photosensitive means in accordance with acoustical vibrations.

I accomplish the above desirable objects in a novel type of light valve under control of mechanical dilations produced by ferromagnetic substances in a magnetic field.

In the drawing which accompanies and forms a part of this specification and in which like reference numerals designate corresponding parts throughout:

Fig. 1 is a schematic representation of one embodiment of the light valve of my invention;

Fig. 2 is a schematic representation of an alternative arrangement of the light valve of Fig. 1;

Fig. 3 is a representation of another form of the light valve of my invention; and

Fig. 4 is a representation of still another form of light valve of my invention.

Referring to the drawing in detail and particularly to Fig. 1, a screen 1 is interposed between a light source 2 and a photoelectric cell 3.

The screen 1 is opaque and is provided with an aperture 4 adapted to direct a beam of light from the light source 2 upon the photosensitive cathode of the photoelectric cell 3. The output of the photoelectric cell 3 is directed to an amplifier 5 having output terminals 6. The amplifier 5 may be of any conventional type adapted to amplify photoelectric currents, such as a resistance-coupled multi-stage thermionic amplifier. A battery 11 is provided as a source of current for the light source 2.

According to my invention, two ferromagnetic rods 7 and 8 are disposed upon opposite sides of the beam of light defined by aperture 4 in the screen 1. These rods 7 and 8 are preferably composed of an alloy which exhibits pronounced magnetostrictive properties, such as the steel alloyed with 46 percent of nickel previously mentioned. A winding is provided around each of the rods 7 and 8 to produce a magnetic field. These windings are connected in series to a battery 9 and a microphone 10. Sound waves incident upon the microphone 10 control the intensity of the magnetic fields produced by the windings around the rods 7 and 8. The rods 7 and 8 are positioned with reference to the light beam from the aperture 4 in a manner such that the magnetostrictive dilations of the rods 7 and 8 intercept the light beam in accordance with the fluctuations of the magnetic field under control of the microphone 10. Variations in the intensity of the light beam thus brought about correspondingly affect the output of the photoelectric cell 3 to produce a modulating current at the output terminals 6 of the amplifier 5 in accordance with the fluctuations in the current from the battery 9 under control of the microphone 10.

Fig. 2 is an alternative arrangement of my light valve in which a photographic film is substituted, for the photoelectric cell of Fig. 1, as the photosensitive means under control of light rays from the light source 2. In this arrangement, a photographic film 12 is provided between two reels 13 and 14. A motor 15 is mechanically coupled to the reel 13 and is adapted to longitudinally move the film 12 in the direction indicated by the arrow. The magnetostrictive dilation of the rods 7 and 8 control the light beam from the aperture 4 to produce a record, on the film 12, of the variations of current under control of the microphone 10. Such a record is, in effect, a record of the sound waves incident upon the microphone 10 and may be used for sound reproduction purposes, such as in sound moving pictures. The elements shown in Fig. 2 correspond to similar elements 110

shown in Fig. 1. It is, of course, to be understood that the representations of Fig. 1 and Fig. 2 are elementary and are intended only to illustrate the operation of my invention. The exact mechanical construction and arrangement of parts will be obvious to those skilled in the art.

Fig. 3 illustrates an alternative form of light valve which may be employed in either the system of Fig. 1 or the system of Fig. 2. A toroidal ferromagnetic core 16 is formed in a manner such that the ends 17 and 18 are in juxtaposition to control a light beam passing between the ends in accordance with a magnetic field applied to the core 16. The core 16 is preferably composed of a nickel-steel alloy, such as used for the rods 7 and 8. A winding is provided about the core 16 and is connected in series with battery 9 and microphone 10. The magnetic field produced by the winding about the toroidal core 16 produces a mechanical dilation of the core in accordance with the intensity of the magnetic field in a manner such as to control the intensity of the beam of light passing between the core ends 17 and 18. The intensity of the magnetic field is under control of the microphone 10, as in Figs. 1 and 2.

Fig. 4 illustrates still another form of the light valve of my invention which may be used in either the system of Fig. 1 or the system of Fig. 2. In Fig. 4, two metallic strips 19 and 20 are positioned, respectively, adjacent to the metallic strips 21 and 22. The metallic strips 19 and 20 are composed of the nickel-steel alloy previously mentioned, and expand when under the influence of a magnetic field. The strips 21 and 22 are composed of nickel which contracts when under the influence of a magnetic field. The pair of strips 19 and 21 and the pair of strips 20 and 22 are rigidly mounted at opposite ends of a base member 23. Two opaque members 24 and 25 are securely mounted on the strips 19 and 21, and on the strips 20 and 22, respectively, as shown. A winding 26 is provided about the strips 19 and 21 and connected in series with another winding 27 provided about the strips 20 and 22. The windings 26 and 27 are connected in series with a battery 28 and a rheostat 32 is provided to regulate the intensity of the permanent field. Another winding 29 is provided about the strips 19 and 21 and is connected in series with a winding 30 provided about the strips 20 and 22. The windings 29 and 30 are connected in series with a battery 9 and microphone 10. The battery 28 and windings 26 and 27, and rheostat 32, provide a steady magnetic field of selected intensity acting upon the pair of strips 19 and 21 and the pair of strips 20 and 22, respectively. The action of the strips 19 and 20 is to expand under the influence of a magnetic field, while the action of the strips 21 and 22 is to contract when under the influence of a magnetic field. The additive effects of the mechanical expansion and contraction in each of the pairs, therefore, causes the members 24 and 25 to be moved in the direction of the arrows when

under the influence of an increasing magnetic field. The windings 29 and 30 produce magnetic fields varying in intensity in accordance with sound waves incident upon the microphone 10. This alternating field produced by the coils 29 and 30 acts upon the steady field produced by the windings 26 and 27 to accentuate the current variations produced by the microphone 10 in a well known manner. The members 24 and 25 are therefore moved to and from each other to intercept a beam of light directed between the ends of the members 24 and 25 in accordance with sound waves impinged upon the microphone 10.

It will now be obvious that I have provided a novel form of light valve operated upon the magnetostrictive principle and which provides a new method for controlling a light beam. It will of course be understood that changes in the form of my invention will readily occur to those skilled in the art, but which will not depart from the intended scope of my invention. I do not, therefore, desire to limit myself to the foregoing except insofar as may be pointed out in the appended claims.

What I claim as new and original and desire to secure by Letters Patent of the United States is:

1. In a light valve for controlling a beam of light, means for producing a controlled electromagnetic field, a pair of bi-metallic members flexibly extending from a rigid support, said members each comprising an element of magnetostrictively expansible material and an element of magnetostrictively contractable material co-acting to produce an accentuated flexure, and shutter elements moved by said bi-metallic members for affecting said beam of light, said bi-metallic members being mounted to produce respectively opposed flexure under the influence of said field whereby the movement of said shutter elements produces an additive controlling effect upon said beam of light.

2. In a light valve for controlling a beam of light incident upon photosensitive means, means for producing a controlled magnetic field, and magnetostrictively operable members mounted within said field and with their corresponding extremities positioned so that they may overlap for movement in the path of said light beam to control the amount of light falling upon said photosensitive means by magnetostrictive dilation of said members under control of said electromagnetic field.

3. In a light valve for controlling a beam of light incident upon photosensitive means, means for producing a controlled magnetic field, and a plurality of members composed of magnetostrictively active material with said field, each having one extremity thereof rigidly mounted and the other extremities disposed so that they may overlap in the path of said light beam whereby the magnetostrictive dilation of said members under influence of said field produces an intercepting effect on said beam of light.

WILLIAM J. HERDMAN.
